RAZOR

George Douglas Jones, Los Angeles, Calif., assignor, by mesne assignments, to Reelshav Corporation, Los Angeles, Calif., a corporation of California

Application July 6, 1948, Serial No. 37,100

3 Claims. (Cl. 30—40)

1

This invention relates to safety razors and is particularly directed to an improved form of razor employing a ribbon-type blade.

The principal object of this invention is to provide a novel form of safety razor employing a ribbon-type blade in which supply and take-up coils are mounted on a carrier for attachment to the razor head as a unit.

Another object is to provide a razor of this type having supply and take-up spools positioned below a razor head together with clamp means above the head which is movable to hold the ribbon blade on a blade seat provided on the top surface of the head.

Another object is to provide a novel form of take-up spool for a ribbon blade razor.

Other objects and advantages will appear hereinafter.

Referring to the drawings:

Figure 1 is a side elevation showing a razor embodying my invention.

Figure 2 is a front elevation partly broken away taken substantially in the direction 2—2 as indicated in Figure 1.

Figure 3 is a sectional side elevation partly broken away taken substantially on the lines 3—3 as shown in Figure 2.

Figure 4 is an exploded perspective view showing the manner of assembly of various parts of the razor.

Figure 5 is a transverse sectional view of the supply container for the ribbon blade.

Figure 6 is a perspective view partly broken away showing construction of the take-up spool for the ribbon blade.

Figures 7 to 10 show a modified form of my invention in which the supply and take-up spools for the ribbon blade are mounted on a carrier, which carrier is adapted to be attached to the razor head as a unit. Figure 7 is a side elevation; Figure 8 is front elevation partly broken away; Figure 9 is a sectional side elevation showing the manner of attachment of the carrier to the razor head; and Figure 10 is an exploded view illustrating the manner of assembly of the carrier and razor head.

Referring to the drawings, the safety razor shown in Figure 1 and generally designated 10 may be provided with a handle 11 having an inclined head 12 rigidly secured at its upper end. A cover 13 overlies the head 12 and may be provided with a central sleeve 14 slidably mounted within a recess 15. The sleeve is interiorly threaded to receive the upper end of the rod 16 which extends upwardly through the handle and

2

which is secured to the knob 17. Rotation of the knob 17 serves to move the cover 13 with respect to the razor head 12. The forward edge 18 of the razor head 12 may be provided with the usual comb teeth, and a pair of upwardly projecting guide pins 19 are mounted at opposite ends of the comb 18. Additional upwardly projecting guides 20 are provided on the razor head, and the upper surface of the razor head extending from the comb 18 to the location of the projecting guides 20 constitutes a seat surface 21 for a blade. The surface 21 is interrupted by openings 22 which extend through the razor head.

A ribbon blade 23 of metallic flexible material is provided with a sharpened portion 24 along one edge thereof. The blade 23 extends from a supply shell 25 to a take-up shell 26, and the blade is coiled within the shells as shown in Figure 5. The blade 23 extends outwardly from the shell 25 through an aperture 27 and extends over the blade seat 21 on the upper surface of the razor head 12. The blade then extends into the aperture 39 in the take-up shell 26, and is wound on a spool or reel 38 provided with an exposed knob 31. Ratchet means comprising a resilient pawl 32 formed from the body of the shell 26 engages ratchet teeth 33 formed on the reel 38 to prevent reverse movement of the ribbon blade 23 with respect to the blade seat 21. The supply shell 25 may be provided with a cap 25a and the take-up shell 26 has an opening in one end to receive a central bearing 38a provided on the reel 38. The extreme ends of the blade seat 21 are rounded as shown at 28 to avoid overstressing the ribbon blade as it enters and leaves the blade seat.

Means are provided on the razor head for holding the shells 25 and 26, and as shown in the drawings this means includes a pair of spring clips 29 and 30. The shell 25 is held within the spring clip 29 and maintained against displacement while the shell 26 is similarly supported and confined by the spring clip 30. Preferably a leader portion on the ribbon blade having an unsharpened edge is provided so that the shells 25 and 26 can be installed within the spring clips 29 and 30 without danger of cutting the fingers of the user. When the ribbon blade 23 is installed in position on the blade seat 21, the knob 31 on the take-up spool 38 is turned to bring the sharpened edge 24 into operative position on the blade seat 21. The handle knob 17 is then rotated to bring the cover 13 downwardly with respect to the razor head and to engage the forward end 34 thereof with the ribbon blade 23 in order to hold it tightly against the seat 21. When

the sharpened edge 24 of the blade becomes dull through use a fresh portion of the blade may be brought into service by first lifting the cover 13 and then winding the knob 31 to withdraw an unused length of ribbon blade 23 from the supply spool 25. The cover is then returned to clamping position by actuation of the handle knob 17. Movement of the cover 13 with respect to the head 12 may be guided by means of the lateral pins 35 extending through the vertical slots 36 provided in the side walls of the cover. The forwardly extending portions 37 of the cover side walls are effective as guards for shielding the sharpened edge 24 of the blade 23 between the locations where it emerges from the shells 25 and 26 and locations where it contacts the curved edges 28 of the blade seat 21.

When the supply of ribbon blade 23 has become exhausted the shells 25 and 26 may be discarded and new shells connected by a fresh 20 blade installed.

In the modified form of my invention as shown in Figures 7 to 10 inclusive, the razor handle 11, head 12, cover 13, knob 17, shells 25, 26 and blade 23 may take the form illustrated and described in the foregoing figures. This modification differs primarily in that the shells are mounted in spaced 25 position on a removable carrier 50 which may be attached to the underside of the razor head 12. The carrier 50 includes a spaced pair of curved gripping elements 51 and 52 adapted to support and hold the shells 25 and 26 respectively, together with a central bridge element 53 extending therebetween. A pair of fingers 54 are mounted under the razor head 12 and attached thereto by means of the rivets 55. These fingers resiliently clamp the bridge 53 against the underside of the razor head 12 and disassembly is prevented by means of engagement of a protuberance 56 on the ends of the fingers adapted to enter the recesses 57 provided on the bridge 53. The fingers are sufficiently resilient to permit installation and removal of the bridge in a direction transverse of the length of the blade 23.

The operation of this form of my invention is substantially the same as that previously described. The cover 13 is moved downwardly to clamp the ribbon blade 23 against the blade seat 21. When the supply of sharpened ribbon blade 23 has been exhausted the shells 25 and 26 may be disposed of as before and new shells installed on the carrier. If desired the carrier and shells

can be formed as a single unit, and in this case the entire unit would be discarded and a new one supplied.

Having fully described my invention, it is to be understood that I do not wish to be limited to the details herein set forth, but my invention is of the full scope of the appended claims.

I claim:

1. A safety razor comprising in combination: 10 a razor head having an upwardly facing blade seat, a flexible ribbon blade on the seat, one end of the blade being coiled in a supply shell and the other being secured to a take-up reel; a spacer member extending between the shell and take-up reel and adapted to maintain them in spaced relationship; means on the razor head for releasably securing the spacer member to the under side thereof; the shell, reel, blade and spacer member being insertable as a unit into operative position on the razor head to position the blade on said seat.

2. A safety razor comprising in combination: a razor head having an upwardly facing blade seat, a flexible ribbon blade on the seat, one end of the blade being coiled in a supply shell and the other being secured to a take-up reel; a spacer member extending between the shell and take-up reel and adapted to maintain them in spaced relationship; spring fingers on the underside of the head for releasably securing the spacer member thereto; the shell, reel, blade and spacer member being insertable as a unit into operative position on the razor head to position the blade on said seat.

3. In a safety razor, the combination of a handle having a head provided with an upwardly facing blade seat; a flexible ribbon blade extending across said seat, one end of the blade being coiled in a supply shell and the other being secured to a take-up reel; a spacer member extending under the razor head and adapted to maintain the shell and reel in spaced relationship; the shell, reel, blade and spacer member being insertable as a unit into operative position on the razor head to position the blade on said seat, and a releasable clamping member movably mounted over the head and adapted to move downwardly to maintain the ribbon blade 45 in position on said blade seat.

GEORGE DOUGLAS JONES.
